US00D948454S

(12) **United States Design Patent** (10) **Patent No.:** **US D948,454 S**
(45) **Date of Patent:** **** Apr. 12, 2022**

(54) **ELECTRICAL CONNECTOR**

(71) Applicant: **Amphenol Corporation**, Wallingford, CT (US)

(72) Inventors: **Marc B. Cartier, Jr.**, Dover, NH (US); **Mark W. Gailus**, Concord, MA (US); **David Levine**, Amherst, NH (US); **Vysakh Sivarajan**, Nashua, NH (US); **John Robert Dunham**, Windham, NH (US); **John Pitten**, Merrimack, NH (US)

(73) Assignee: **Amphenol Corporation**, Wallingford, CT (US)

(**) Term: **15 Years**

(21) Appl. No.: **29/739,366**

(22) Filed: **Jun. 24, 2020**

Related U.S. Application Data

(63) Continuation of application No. 29/666,525, filed on Oct. 12, 2018, now Pat. No. Des. 892,058.

CLAIM

The ornamental design for an electrical connector, as shown and described.

DESCRIPTION

FIG. 1 is a top, front, left side perspective view of an electrical connector according to our new design;

FIG. 2 is a top, rear, right side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

(Continued)

The broken lines depict portions of the electrical connector that form no part of the claimed design.

1 Claim, 8 Drawing Sheets
